KNEELER FOR CHAIRS

Werner E. Clarin, White Pigeon, Mich., assignor to Clarin Mfg. Co., Chicago, Ill., a corporation of Illinois
Filed Dec. 27, 1960, Ser. No. 78,731
6 Claims. (Cl. 297—425)

The present invention relates to a kneeler attachment for use in churches.

Kneelers, which are used in churches of various denominations, may be conveniently provided by fixing them to the rear of chairs. It is desirable to have available chairs with kneelers to provide seating space in church when needed, but which can be used for other purposes when they are not needed for church services. This problem has been partially met by devices of the type shown in Patent No. 2,548,098 in which kneelers have been pivotally attached to the legs of the chairs in such a way that they could be folded up between the legs of the chair when the chair is not being used for church services. However, these permanently attached kneelers add considerable weight to the chairs and are relatively expensive. Furthermore, the added weight presents a substantial problem when a number of these chairs have to be transported any considerable distance.

Accordingly, it is the principal object of the present invention to provide an improved, readily detachable kneeler attachment for chairs. It is a more specific object of the present invention to provide such a kneeler attachment which is a unitary structure requiring no additional pieces which may be misplaced or lost. It is still another object of the present invention to provide a kneeler attachment which is rugged and durable so as to give long service but which is at the same time simple and economical.

Other objects and advantages of the invention will become obvious from the following description and accompanying drawings.

In the drawings:

FIGURE 1 is a perspective view of a folding chair and a kneeler attachment assembled together and embodying various features of the invention, the kneeler attachment being shown in the extended position;

FIGURE 2 is generally similar to FIG. 1, with the kneeler attachment in the folded position;

FIGURE 3 is a side view of the chair and kneeler attachment shown in FIGS. 1 and 2, the chair and the kneeler attachment both being in the folded position;

FIGURE 4 is an enlarged fragmentary view of the chair and kneeler attachment as seen in FIG. 2, illustrating particularly a unitary bracket structure utilized in attaching the kneeler to a cross brace of the chair, the latch of the bracket structure being shown in the unlock position;

FIGURE 5 is a side view taken generally along line 5—5 of FIG. 4, but showing the latch in the locking position and supporting arms for the kneeler in their horizontal position; and

FIGURE 6 is a sectional view taken generally along line 6—6 of FIG. 4.

Very generally, the illustrated device comprises a kneeler attachment 10 for a chair 12 having a pair of spaced-apart rear legs and a cross brace connecting the legs. The kneeler attachment 10 comprises a platform 14, a pair of arms 16 which extend forwardly from opposite sides of the platform 14, and means 18 for detachably connecting the arms to the rear legs of the chair. The illustrated connecting means 18 comprises a bracket 21 on the forward end of each arm. Each bracket has a body section 22 and a pair of flange sections 24 and 25 fixed to the body section at an angle thereto. The

2

pair of flange sections 24 and 25 of each bracket 21 also extend at an angle with respect to each other, such that one of the flange sections is disposed to engage the chair leg and the other of the flange sections is disposed to engage the cross brace of the chair. Finally, the device includes locking means 26 movable relative to the bracket 21 for cooperation with the bracket to secure it to the chair. The illustrated kneeler attachment 10 is constructed so that it may be folded between the legs of the chair, as shown in FIG. 2, as well as being detached therefrom.

While the illustrated kneeler attachment 10 may obviously be utilized with other types of chairs, it is particularly adapted for use with folding chairs, as its advantages are best utilized in situations calling for the use of folding chairs. These situations are those, where, because of considerations such as space and mobility, devices which may be folded or disassembled and relocated or stored are particularly advantageous. The kneeler attachment 10, which meets these requirements as it may be detached from the chair or may be folded with it as shown in FIG. 3, will accordingly be described as utilized with the folding chair 12.

It should also be understood that while the present description of the device is directed to the preferred embodiment shown in the drawings, the principles herein disclosed may be applicable to other types of chairs having differing constructions and differing brace arrangements.

30 The illustrated folding chair 12 comprises a pair of leg frames 62 and 64 pivotally connected at 66 to form an X in extended or unfolded position and provide a support for a seat 68. The leg frames 62 and 64 are formed from strips of sheet metal, the lateral edges of which 35 have been turned inwardly to provide reinforcing beads 70 with a flat space between them. Such a strip of metal is bent into the form of a U to provide the frame 62 with parallel portions which are spanned by cross or transverse braces 72 and 74 adjacent to and on opposite sides of 40 the pivot 66.

The frame 62 provides the front legs and back support for the chair 12. At the upper end or bight of the U there is arranged a curved plate of sheet metal to constitute a back rest 78.

45 The frame 64 comprises a pair of these formed strips providing the rear legs which are connected by a pair of spaced-apart cross or transverse braces 78 and 30. The upper ends of the legs 28 are pivotally connected to the seat 68, which is pivotally suspended from the frame 62 by a pair of links 80. At their lower extremities the frames 62 and 64 are provided with suitable pads 82.

The cross brace 30 to which the kneeler attachment 10 is connected extends between the rear legs 28 adjacent their lower ends and generally perpendicularly thereto. As 55 shown in FIG. 6, the flat ends 31 of the brace 30 are bent forwardly at approximately a right angle and are fixed to the legs 28 in a rigid manner, such as by bolting, riveting or welding, to withstand the forces exerted upon the brace 30 by the repeated impacts applied to the kneeler attachment during its use. The remainder of the illustrated cross brace 30, i.e., the portion intermediate its ends 31, shown in section in FIG. 4, is an elongated metal strip or strap formed similarly to the legs 28 by having its lateral edges 32 turned inwardly toward the front of the chair 12. The brace 30 also has a longitudinally extending depression providing a center rib 34 on the rearward face of the brace 30.

70 The kneeler attachment 10 shown in the drawings is a unitary structure which may be attached to the chair and subsequently readily removed from the chair and stored separately. It has no extra parts to be misplaced or lost between times when it is used. As noted above, the

kneeler attachment 10 may also be folded between the legs of the chair (FIGS. 2 and 4).

The illustrated kneeler attachment 10 includes a rectangular kneeler platform 14 which may be comprised of a solid base, suitable cushioning material such as foam-rubber overlying it to provide knee comfort, and a covering such as plastic or leather for holding the cushioning material in place. The side to side dimension of the platform 14 is sufficiently small so that it will fit between the legs 28 when the chair is folded (FIG. 2). The remaining parts of the kneeler attachment 10 are preferably constructed of relatively heavy duty metal to give longer, maintenance free use under the repeated impacts to which the attachment is subjected during use.

As seen best in FIGS. 1 and 2, the kneeler platform 14 is secured to a generally U-shaped supporting frame structure 40 which includes a transversely extending center portion and a pair of elongated arms 16 which extend forwardly from opposite sides of the kneeler platform 14. Pivottally connected to the frame structure 40 is a kneeler leg structure 42 which includes a pair of kneeler legs 43 located at either side of the kneeler platform 14. Pivottally connected to the kneeler leg structure 42 are a pair of elongated links 44. Each of the links 44 is pivottally connected at one end to one of the kneeler legs 43 at a point spaced downwardly from the pivotal connection of the kneeler leg structure 42 with the frame structure 40. Each of the links 44 extends forwardly in generally parallel and underlying relation to one of the arms 16.

The forward ends of the arm 16 and the link 44 on each side of the attachment 10 are pivottally attached to a connecting means 18 which serves to detachably connect the kneeler attachment 10 to the chair 12. This connection is at approximately the two junctions of the cross brace 30 with rear legs 28.

Each of the connecting means 18 shown in the drawings is a unitary bracket structure 20, which includes a generally U-shaped bracket 21 and a latch or fastener 54 pivottally supported on the bracket 21. A single bracket structure 20 will now be described, it being understood that each kneeler attachment 10 is provided with a pair of these structures which are alike except for the obvious reversal of parts between brackets used on opposite sides of the device. In this connection, the illustrated bracket 21 is constructed with certain of its parts, yet to be described, duplicated, so that a single type stamping of the bracket 21 can be used to make a bracket structure for either side of the device.

As shown in FIGS. 4, 5 and 6, the bracket 21 of the illustrated bracket structure 20 has the center or body portion 22, a first leg providing a connecting plate section 27, and a second leg providing the flange section 25. The connecting plate section 27 is a generally vertically disposed plate to which the forward ends of an arm 16 and a link 44 are pivottally connected as by rivets 48. The link 44 is suitably inwardly offset to clear the leg 16 when the kneeler attachment 10 is folded (as best seen in FIGS. 2 and 4).

The generally flat body section 22 of the bracket 21 is adapted to fit generally flushed against the rearward face of the cross brace 30 at a point adjacent one of the chair legs 28. The body 22 is provided with a transverse depression 23 which generally mates with the center rib 34 of the brace 30 to aid in positioning and maintaining the bracket 21 in place relative to the brace 30. The upper end of the body section 22 is provided with the curved, generally horizontally extending flange section or hook 24 which hooks over and engages the upper edge of the cross brace 30, serving to support the bracket 21 upon the brace. A second transverse depression 23' and a second hook 24' on each bracket 21 make it possible to use a single type stamping for both sides of the device as noted above.

The flange section 25 of the bracket 21 is formed into

an elongated, generally vertically extending, semi-circular flange which engages the rear bead 70 of the chair leg 28, as seen in section in FIG. 6. The engagement of the flange section 25 with the bead 70 serves to position the bracket 21 and to limit its transverse movement relative to the chair 12. Also, the flange section 25 is preferably sufficient in length to substantially prevent the bracket 21 from wobbling relative to the chair.

A generally rectangular latch, fastener, or locking plate 54, having ends 58 and 60, is pivotally supported intermediate its ends on the body section 22, as by means of a suitable rivet 56, to provide the locking means 26 for the illustrated embodiment. The latch 54 moves in a plane generally parallel to the body section 22 and it has one end 58 offset outwardly from the body section, so that the end 58 moves in a plane generally parallel to but spaced-apart from the body section 22. The spacing should be sufficient so that when the latch 54 is rotated to the generally vertical position, its end 58 will move past the lower edge of the cross brace 30 and assume a position directly in front of the brace 30 (shown in FIG. 5) so as to lock the bracket structure 20 upon the chair 12. The other end 60 of the latch 54 is adapted to be grasped by the user to rotate the latch. The end 60 is considerably longer than the end 58 to provide mechanical advantage, and it is bent at its extremity to make it easier to hold and to operate.

Thus, the unitary kneeler attachment 10 may be attached to the chair 12 by simply hooking the horizontal flange sections 24 of its two brackets 21 upon the upper edge of the cross brace 30, while engaging the vertical flange sections 25 of the brackets 21 with the beads 70 of the legs 28, and then rotating the latches 54 of the bracket structures 20 into the generally vertical position, as shown in FIG. 5, to lock the two unitary bracket structures 20, and thus the kneeler attachment 10, in place. To remove the kneeler attachment 10, the latches 54 are merely rotated so as to release their respective bracket structures 20, and the entire attachment 10 may be removed from the chair for repair, storage, or the like. Thus, the illustrated unitary kneeler attachment 10 requires no screws, nuts, or bolts, but attaches firmly to the chair simply and quickly, and may be removed from the chair in the same simple and quick manner.

While some variations in the disclosed structure have been mentioned, various other details of the illustrated device may also be varied without departing from the scope of the invention. Various features of the present invention are set forth in the following claims.

What is claimed is:

1. A kneeler attachment for a chair having a pair of spaced-apart rear legs and a cross brace extending between the legs, said kneeler attachment comprising a platform, a pair of arms extending forwardly from opposite sides of said platform, and means on said arms for detachably connecting them to the rear legs of the chair, said connecting means comprising a bracket on the forward end of each arm, each of said brackets having a body section and a pair of flange sections fixed to said body section, said pair of flange sections being disposed with respect to each other so that one of said flange sections is arranged to engage a chair leg and the other of said flange sections is arranged to engage the cross brace of the chair, and locking means movable relative to said bracket for cooperation with said bracket to secure it to the chair.

2. A kneeler attachment for a chair having a pair of spaced-apart rear legs and a cross brace extending between the legs, said kneeler attachment comprising a platform, a pair of arms extending forwardly from opposite sides of said platform, and a unitary bracket structure on each of said arms for detachably connecting its forward end to a rear leg of the chair, each of said unitary bracket structures comprising a bracket and locking means, each of said brackets having a body section and a pair of flange sections fixed to said body section at an angle thereto, said

pair of flange sections being disposed at such an angle with respect to each other that one of said flange sections is arranged to engage the chair leg and the other of said flange sections is arranged to engage the cross brace of the chair, said locking means being movably mounted on said bracket for movement relative thereto for cooperation with said bracket structure in securing said bracket structure to the chair.

3. A kneeler attachment for a chair having a pair of spaced-apart rear legs and a cross brace extending between the rear legs, said kneeler attachment comprising a kneeling platform, a pair of arms extending forwardly from opposite sides of said platform, and a unitary bracket structure on each of said arms for detachably attaching its forward end to a rear leg of the chair, each of said unitary bracket structures comprising a bracket and a locking member, each of said brackets having a body section and a pair of flange sections fixed to said body section and extending at an angle thereto, said flange sections being disposed generally at such an angle to each other that one of said flange sections is arranged to engage the chair leg to limit transverse movement of the bracket relative thereto, and the other of said flange sections is arranged to engage the upper edge of a portion of the cross brace adjacent that chair leg to support said bracket, said locking member being movably mounted on said bracket for movement in generally parallel spaced relation to one of said bracket sections for cooperation with said bracket structure in securing said bracket structure to the chair.

4. A kneeler attachment for a chair having a pair of spaced-apart rear legs and a cross brace extending between the rear legs, said kneeler attachment comprising a kneeling platform, a pair of arms extending forwardly from opposite sides of said platform, and a unitary bracket structure on each of said arms for detachably attaching its forward end to a rear leg of the chair, each of said unitary bracket structures comprising a bracket and a locking member, said bracket having a body section and a pair of flange sections fixed to said body section and extending at an angle thereto, said flange sections being disposed generally at such an angle to each other that one of said flange sections is arranged to engage the chair leg to limit transverse movement of the bracket relative thereto and the other of said flange sections is arranged to engage the portion of the cross brace adjacent that chair leg, said leg engaging flange section being formed and aligned to engage a length of the chair leg to limit transverse movement and wobbling of the bracket relative to the chair leg, said brace engaging flange section being formed to engage the upper edge of the brace to support said bracket, said locking member being pivotally mounted on said bracket for movement in generally parallel spaced relation to one of said bracket sections for cooperation with said bracket structure in securing said bracket structure to the chair.

5. In combination with a folding chair having a pair of rear legs which are braced adjacent their lower end by a cross brace connected between said legs, a removable kneeler attachment comprising a kneeler platform, a pair of arms extending forwardly from said platform along opposite sides thereof, and a unitary bracket structure pivotally connected to the forward end of each of said arms for detachably attaching said forward end to one of said rear legs of said chair, each of said unitary bracket structures comprising a generally U-shaped

bracket and a latch pivotally mounted on said bracket, each of said brackets having one leg section thereof providing said pivotal connection with said arm, the center section of said bracket having facing engagement with said cross brace of said chair, said center section having a curved flange section engaging the upper edge of said cross brace to support said bracket, and the other leg section of said U-shaped bracket being formed to provide a flange for engaging a length of the rear leg of said chair to limit movement of said bracket transverse of said chair leg, said pivotally mounted latch being movable in generally parallel, spaced relation to said center section for cooperation therewith in gripping opposite sides of said cross brace, whereby said unitary bracket structure can be releasably locked in position on said chair and said kneeler platform can be moved between a position extending rearwardly of said chair and a folded position wherein said kneeler platform and arms are disposed between said rear legs of said chair.

6. In combination with a folding chair having a pair of rear legs which are braced adjacent their lower end by a cross brace connected between said legs, a removable kneeler attachment comprising a kneeler platform, a supporting frame structure for said platform, including a pair of arms extending forwardly from said platform along opposite sides thereof, a kneeler leg structure for said platform pivotally connected to said frame structure, a pair of generally parallel, spaced-apart links pivotally connected to said kneeler leg structure and extending forwardly therefrom, respectively, in generally parallel, underlying relation to one of said arms, and a unitary bracket structure pivotally connected to the forward ends of the arm and link on each side of said platform for detachably attaching said forward ends to one of said rear legs of said chair, each of said unitary bracket structures comprising a generally U-shaped bracket and a latch pivotally mounted on said bracket, each of said brackets having one leg section thereof providing said pivotal connection with said arm and link, the center section of said bracket having facing engagement with said cross brace of said chair, said center section having a curved flange section engaging the upper edge of said cross brace to support said bracket, and the other leg section of said U-shaped bracket being formed to provide a flange for engaging a length of the rear leg of said chair to limit movement of said bracket transverse of said chair leg, said pivotally mounted latch being movable in generally parallel, spaced relation to said center section for cooperation therewith in gripping opposite sides of said cross brace, whereby said unitary bracket structure can be releasably locked in position on said chair and said kneeler platform can be moved between a position extending rearwardly of said chair and a folded position wherein said kneeler platform, frame structure, links and arms are disposed between said rear legs of said chair, and wherein said kneeler leg structure is folded against the bottom of said kneeler platform.
